UNITED STATES PATENT OFFICE.

KARL P. McELROY, OF WASHINGTON, DISTRICT OF COLUMBIA.

LABORATORY APPARATUS.

1,254,048.

Specification of Letters Patent. Patented Jan. 22, 1918.

Application filed May 16, 1917. Serial No. 169,109.

To all whom it may concern:

Be it known that I, KARL P. McELROY, a citizen of the United States, residing at Washington, in the District of Columbia, 5 have invented certain new and useful Improvements in Laboratory Apparatus, of which the following is a specification.

This invention relates to laboratory apparatus and it comprises a steam generating device provided with a water receptacle, 10 means for delivering water therein, means for maintaining a constant level of the water in the receptacle, and a branch, advantageously a pipe, leading from the receptacle at a point below the level of the water and extending upwardly to a point above the level of the water in the receptacle whereby the water may be heated in this branch at a point corresponding to the level 15 of the water in the receptacle and whereby the steam thus generated can be directed from this branch to a point of use; and the invention comprises a vertical water tube provided with an adjustable tube or over- 20 flow for maintaining a given level in the first tube and an open ended tube or pipe communicating with the side of the first tube below the water level therein and extending upwardly beyond the water level 25 together with heating means for the open ended tube; all as more fully hereinafter set forth and as claimed.

For laboratory purposes it is often desirable to have a source of steam adapted to 30 be run by a Bunsen burner and to furnish small quantities of steam at 100° C. or higher, for various chemical reactions and for heating purposes. It is further desirable that such an apparatus be quick acting, 35 small and convenient of form. Boilers small enough for use on a laboratory desk are unhandy and require too much attention. It is the object of the present invention to meet this requirement.

To this end, I provide a vertical tube, 40 which may be of glass or metal but is advantageously partly of glass, and closed at the lower end. Through this closed end I pass a vertical glass or metal tube to serve 45 as an overflow pipe; making it adjustable to allow variation in water level. An open

ended steam tube is connected to the side of the vertical tube and bent or sloped upward so that its discharge end, or open end, is at a higher level than the normal water 55 level. This steam tube is best made of copper. On now placing a burner under the steam tube at the water level, steam is generated in quantity and by placing other burners along the tube it may be super- 60 heated to any desired degree. The steam is discharged in large volumes but not ordinarily under any great pressure; the pressure not exceeding the water height in the vertical tube. Ordinarily, I do not have a 65 steam pressure more than that corresponding to an inch or so of water. Such a pressure however is sufficient for all ordinary heating and chemical purposes in the laboratory. If, for example, an open casing 70 is to be heated by blowing superheated steam therein, there is of course no back pressure; and even if the casing is closed the condensation as the heating goes on prevents production of pressure by the further 75 introduction of the steam. The apparatus can of course be modified to work under more or less pressure, but this detracts from its simplicity and where steam under pressure is wanted other means are available. 80 The object of the present invention is to provide means for delivering comparatively large amounts of free steam at any temperature which may be desired.

In the accompanying drawings I have 85 shown one form of a specific embodiment of my invention.

In this showing

Figure 1 is a perspective view of the apparatus of my invention shown as mounted 90 upon an ordinary laboratory stand; and

Fig. 2 is a longitudinal vertical section throughout the complete apparatus.

In these drawings, 1 indicates the base of an ordinary laboratory stand having the 95 upright 2 and the clamp 3 attached thereto by means of the adjustable clamp 4. This stand and the brackets and clamps form no part of my invention but are shown to illustrate one method of conveniently mounting 100 my steam generating apparatus upon the ordinary stand used in a chemical laboratory.

The complete apparatus of my invention may be made up of a plurality of pipe fittings. I have shown the section of pipe 5 having a shoulder 6 and screw threaded upon 5 per extension 7. Tube 8, advantageously of glass, is held upon the shoulder 6 by means of the nut 9, packing 10 being employed if necessary. The bottom extension 11 of the section 5 is provided with a stopper 12 10 which may be of cork or other suitable material, such stopper having an opening 13 through which is inserted the overflow pipe or constant level maintaining device 14. This level maintaining device may be a simple 15 copper tube or a glass tube and it is adapted to be raised and lowered to extend upwardly in the tube 8.

At the top of the tube, water delivering means 15 are provided. As the water is delivered into the tube 8 through means 15 it fills the tube up to the level indicated at A whereupon the surplus water will overflow into the level maintaining device 14 and thence to waste. The section 5 is provided 25 with an extension 16 which is preferably screw threaded into the section 5 at 17 and at its other end this tube 16 is provided with an elbow 18 screw threaded at 19 to such tube and to this elbow in turn is connected 30 a nipple 20 having screw threaded portion 21 to which is attached the steam generating pipe 22 advantageously of copper or other high heat conducting metal. The water level in the steam directing portion 22 is maintained at a level B corresponding to 35 the level A in the water tube 8. This steam directing tube 22 is preferably directed upwardly in order that the surface of the water at B can spread out in a relatively 40 thin layer to facilitate rapid generation of steam. The steam directing tube 22 may be of any length desired and as many different burners as are needed may be placed under it, one such burner indicated 45 by the numeral 23 being placed directly under the water in tube 22 at B. This burner rapidly causes the water of this thin layer B to flash into steam. Another burner 24 may be placed farther along the length of 50 the steam directing portion 22 to superheat the steam and other burners may be used, the number depending upon the temperature to which it is desired to heat the steam. I have found that with a tube of one quarter 55 of an inch in diameter and about two feet long I can supply a quantity of steam at a temperature sufficient to char wood. The temperature at which the steam may be delivered is only limited by the melting point 60 of the material of the steam delivering tube 22.

When the steam is delivered, for instance, into a closed casing there is likely to be a

slight back pressure in the tube 22 which pressure will be transmitted to the water in 65 tube 8 and therefore the tube 14 in tube 8, under these conditions, may have to be positioned slightly higher than the level of the water at B in steam directing tube 22.

The operation of the device is obvious 70 from the foregoing description. The device is exceptionally compact and simple in construction comprising a relatively few number of simple parts. These parts may be easily assembled and may be made of cheap 75 material. In this compact form the device is convenient in a laboratory, and the arrangement of the parts are such that it can be quickly and securely mounted upon a stand as is shown in Fig. 1.

When it is desired, a hood of asbestos or the like 25 may be used to retain the heat around the steam directing portion of the apparatus, but ordinarily this is not necessary as in a laboratory the use of any number 85 of Bunsen burners is convenient and their use is relatively inexpensive.

What I claim is:—

1. Apparatus for generating steam comprising a water receptacle, means for constantly delivering water therein, means for maintaining a constant level of water therein, a branch leading from the receptacle from a point below the level of the water and extending upwardly to a point above 95 the level of the water whereby the water may be heated in the branch at a point corresponding to the level of the water in the receptacle to generate steam in said branch.

2. An apparatus according to claim 1 in 100 which the means for maintaining constant level of water comprises an adjustable tube open at both ends.

3. An apparatus according to claim 1 in which the water receptacle comprises a 105 holder and a separable tube set therein.

4. An apparatus according to claim 3 provided with a tube located in the receptacle and adapted to be raised or lowered.

5. An apparatus according to claim 1 in 110 which the branch is removably secured to the water receptacle.

6. An apparatus according to claim 1 in which the branch comprises a plurality of 115 separable parts.

7. An apparatus according to claim 1 in which the water receptacle comprises a section of pipe, a tube in communication with said section and in which the branch is removably secured to said section.

8. An apparatus in accordance with claims 1 to 7 inclusive in combination with means for heating the water in the branch.

9. An apparatus in accordance with claim 8 in which in addition to the said heating 125 apparatus there is additional heating appa-

ratus for superheating the steam generated in the branch.

10. An apparatus for generating steam comprising a water receptacle, means for delivering water thereto, means for permitting water to overflow from a certain point in said receptacle, a pipe leading from the said

receptacle below said point and extending beyond the confines of said receptacle to a level at least equal to said point, and means 10 for heating the water in said pipe.

In testimony whereof, I affix my signature hereto.

K. P. McELROY.
